UNITED STATES PATENT OFFICE.

AARON M. ADAMS AND MAXWELL W. LANDAU, OF PHILADELPHIA, PENNSYLVANIA.

CAP-SIZE-REDUCING DEVICE.

1,409,810.

Specification of Letters Patent. Patented Mar. 14, 1922.

Application filed January 12, 1920, Serial No. 350,864. Renewed January 26, 1922. Serial No. 532,028.

To all whom it may concern:

Be it known that we, AARON M. ADAMS and MAXWELL W. LANDAU, citizens of the United States, residing at Philadelphia, in 5 the county of Philadelphia, and State of Pennsylvania, have invented new and useful Improvements in Cap-Size-Reducing Devices, of which the following is a specification.

10 The invention relates to apparel and more particularly to head gear and has for an object to provide a device for reducing the size of caps and other soft or flexible head gear.

Among other features the invention comprehends a spring-like member which can be 15 conveniently disposed within the cap or similar head gear to reduce the head size thereof without detracting from the appearance of the cap or destroying its shape, the device 20 being simple in its construction and therefore capable of being cheaply manufactured and readily applied.

We are aware that various forms of head size reducing devices for head gear have 25 been used heretofore, but many of these devices are adapted only to hats which are of a stiff nature, such as derbies and the like and which furthermore comprehend the interposition of the device between the sweat 30 band and the crown, merely tending to cause the sweat band to project beyond the inner edge of the brim and therefore such devices are mainly of a circumferential nature and must of necessity be so, in order to effect 35 an equal bulging of the sweat band entirely around the same.

Our invention is particularly adapted to caps which ordinarily do not have the sweat band extending entirely around the same, but 40 merely have the sweat band at the front adjacent the inner end of the peak, our device being so disposed that it will not be normally seen and in its operation will tend to straighten out the peak, thus exerting a 45 pull upon the rear soft portion of the cap, causing the latter to more firmly grip the head.

In the further disclosure of the invention, reference is to be had to the accompanying 50 drawings constituting a part of this specification, in which similar characters of reference denote corresponding parts in all the views, and in which,—

Figure 1—is a bottom plan view of a cap 55 showing our device applied thereto, parts

being broken away to disclose the underlying structure.

Figure 2—is a perspective view of the device by itself.

Figure 3—is a fragmentary elevation 60 partly in section taken through a portion of the cap showing the manner in which each end of the device is held in engagement with the cap, and

Figure 4—is a perspective view of our de- 65 vice showing the same provided with a suitable covering.

Referring more particularly to the views the device in its entirety is indicated by the numeral 10 and consists of a single strip of 70 spring-like resilient material 11 of a substantially flat nature and which at its medial portion has an integral pin 12 struck therefrom and at right angles thereto, each end of the strip of material being fashioned to 75 provide a pointed tapering prong 13 and a shorter blunt prong 14 acting substantially as a stop member, as will be hereinafter more fully described.

In the application of the device to a cap 80 15, the device is disposed beneath the sweat band 16, between the sweat band and the peak, the device being bent into a substantially crescent shape, with each of the prongs 13 being arranged to extend into and 85 through the material or lining 18 of the cap and grip into the ends of the peak. This causes the peak to substantially straighten out and lie flat and thus causes a slight bulge 90 of the sides of the cap as at 19, further causing the rear 20 of the cap to be pulled toward the peak so that in the application of the cap to the head the rear or back of the cap will snugly fit the head. As the prongs 13 extend into the material from which the 95 peak 17 is formed, the stop members 14, engaging with the material limit the inward movement of the prongs and at the same time afford sufficient grip on the surface of the material to prevent displacement of the 100 device, the medial pin 12 being also adapted to extend into the peak at its central portion as shown, so that the device will be securely positioned and as will be readily noted, cannot be easily seen and will be substantially covered by the sweat band of the cap.

Thus with a device of the character described, it will be seen that a cap which normally does not quite fit the head as snugly 110

as it should, can be readily shaped or fashioned to provide an effective fit on the head by the use of our device, disposed in the manner mentioned, and it will be apparent that a device of this character may be cheaply manufactured and not only serves the function of reducing the cap size, but also acts as a support or backing for the peak, tending to maintain the latter in its proper shape.

As shown in Figure 4, the device may be provided with a suitable covering which may be of any desired form of material such as leather cloth or a webbing of some sort as shown, and indicated by the numeral 21, the ends of the covering being secured to the device by any form of an adhesive composition, paraffin or the like, as indicated at 22. It will of course be understood that it might be desirable to dip the devices and coat them with a rubber composition, and it will be clear that we do not limit ourselves to any

particular form of covering and that any desired material or composition may be employed for this purpose.

Having described our invention, we claim, As a new article of manufacture a cap size reducing device comprising a strip-like piece of resilient material having a single prong extending laterally thereto and stamped out from one side of the said piece of material at the center thereof, and a forked extension projecting from each end of the piece of material and in the longitudinal plane thereof, one limb of said forked extension constituting a pin to engage into the material of the cap at or adjacent to the points of connection of the ends of the vizor with the material of the body of the cap.

In testimony whereof we affix our signatures.

AARON M. ADAMS.
MAXWELL W. LANDAU.
